UNITED STATES PATENT OFFICE.

HARRY C. GAMAGE, OF NEW YORK, N. Y., ASSIGNOR TO D. P. COMPANY, A CORPORATION OF NEW JERSEY.

JOURNAL-BOX LID.

1,180,486.

Specification of Letters Patent. Patented Apr. 25, 1916.

Application filed December 9, 1913. Serial No. 805,528.

To all whom it may concern:

Be it known that I, HARRY C. GAMAGE, a citizen of the United States, and resident of the city, county, and State of New York, 5 have invented certain new and useful Improvements in Journal-Box Lids, of which the following is a specification.

This invention relates to an improved construction for a journal box lid or cover for 10 car axle boxes.

The object of the invention is to provide a lid or cover which shall be simple in construction, light in weight and cheaply manufactured. The hard use to which car axle 15 boxes are put and the continual jarring to which they are subjected renders it important that the lid or cover shall not only be of such construction as to be readily opened to provide access to the box but that the 20 same shall be securely held in position when closed in such a manner as to provide against the same becoming jarred loose or open.

In carrying out the invention, I provide 25 a single piece of resilient material, preferably rectangular in shape, which is bent back upon itself and curved to conform to the shape of the journal box. The lid is received in grooves in the journal box wall 30 and, on account of its resiliency, is self-sustaining in position, thus providing a very simple form of lid for the box.

In order to provide against the oil working to the outside of the box an angular or 35 offset portion is formed on one side of the lid, which performs the dual function of an oil shed and a lock to hold the lid in position when closed or partly open, as will be explained more fully hereinafter.

40 The above and other features of the invention will be pointed out more fully in connection with the description of the embodiment of the same illustrated in the accompanying drawings, in which like parts in the 45 several views have been given the same reference numerals.

Figure 1 is a front elevation of a journal box showing my improved form of lid in its closed position. Fig. 2 is a sectional side ele-

vation on the line 2—2 of Fig. 1, also showing the lid in its closed position. Fig. 3 is a sectional view, similar to Fig. 2, showing the lid in its partly open or intermediate position. Fig. 4 is a sectional view, similar to Fig. 2, showing the lid in its open position. 50 55

A portion of a journal box, of usual construction, is shown at 1. The front of the box is usually curved and provided with grooves, such as 2, on either side thereof. The upper half of the front of the box is 60 open and the lower half is closed by the wall 3.

The lid is formed of a single resilient flat plate which is bent back upon itself, as shown at 4 and 5, and is formed with an offset or inwardly bent portion 6 at the lower edge of the inside portion 5 extending over the upper edge of the wall 3 when the lid is in its closed position. A curved end portion 7 may be formed as a part of the side 5 of 70 the lid or may be a separate piece attached to the lid at the lower end of the side 5, as shown in the drawings. This portion forms a convenient means for raising and lowering the lid and also forms a latch for holding 75 the bent over portions 4 and 5 together to relieve the tension when the lid is to be opened.

When the lid is moved up to its closed position, as shown in Fig. 2, the side portions 4 and 5 spring apart, causing the offset portion 6 to engage or latch over the upper edge of the inner wall 3 of the box, thus locking the lid securely in position. When in this position, the angular or offset portion 6 extends 85 slightly beyond the inner surface of the inner wall 3 of the box, causing the oil running down upon the inner side 5 of the lid to drop on the interior of the box and preventing the same from dropping or working 90 to the outside of the journal box.

When it is desired to open the lid, the curved lower portion 7 is engaged by a suitable tool underneath or in the opening 8 and is pulled outwardly to disengage the offset 95 portion 6 from the wall 3, as indicated in dotted outline in Fig. 2. The lid is then slid downwardly in the slots 2 to its open posi-

tion where it rests against a removable stop 9 as shown in Fig. 4.

In order that it may not be necessary to hold the lower portion 7 in its outer position 5 while sliding the lid downwardly, the inner end of this curved portion 7 is formed so as to latch over and engage the lower edge of the outer portion 4 of the lid, as shown in dotted outline in Fig. 2, thus relieving the 10 tension between the lid and the walls of the groove, permitting the same to slide freely to its open position. This permits of a much stiffer construction which insures the holding of the lid rigidly in place and prevents 15 all rattling or looseness of the same in the box.

When the box or bearings have become heated it is sometimes desirable to run with the lid partly open, to provide ventilation, 20 etc. For this purpose a transverse recess or slot 10 is provided in the wall 3 in which the offset portion 6 of the lid engages when the same is moved downwardly to an intermediate position, as shown in Fig. 3. To 25 hold the lid in this position it is only necessary to release or unlatch the curved portion 7 from the lower edge of the side 4 of the lid, permitting the offset portion 6 to enter the recess 10, as shown in Fig. 3.

30 Another result is accomplished by reason of the construction of the lid just described, namely, the provision of an air space between the two spaced sides and closed ends or bent over portions which effectually prevents dust, rain, etc., from working past both portions of the lid.

It will thus be seen that a very simple form of construction is provided which has many advantages and new functions and 40 which will meet the severe requirements for an article of this class in a most efficient manner.

What I claim is:

1. A journal box lid consisting of a plate 45 of resilient material bent back upon itself to form closed front and back parallel side walls and a closed upper end with an air space between, the lower end of one of said side walls being formed to substantially close the lower end of said air space.

2. In combination with a journal box having an opening in the front wall thereof and having on opposite sides of said opening portions formed in which a lid is received and adapted to be slid to several positions with respect to said opening, said front wall having portions formed and adapted to be engaged by said lid in its open and closed positions, and also having 55 a portion formed to be engaged by said lid when in an intermediate position, of a lid comprising a single piece of resilient material bent back upon itself to form two

spaced side walls with closed upper end and adapted to be positioned in and formed 65 to engage said portions of the journal box and to be self-sustaining in its open, intermediate or closed positions.

3. In combination with a journal box having an opening in the front thereof and 70 having on opposite sides of said opening portions formed in which a lid is received and adapted to be slid to several positions with respect to said opening, of a lid comprising a single piece of resilient material 75 bent back upon itself to form two spaced side walls with closed ends and having an offset portion on one side wall thereof adapted to form an oil shed and also to engage one edge of said opening in the 80 journal box to lock the same in position.

4. In combination with a journal box having an opening in the front thereof and having on opposite sides of said opening portions formed in which a lid is received and 85 adapted to be slid to several positions with respect to said opening, of a lid comprising a single flat plate of resilient material bent back upon itself and having a portion at one end formed to engage and latch over the 90 opposite bent over portion.

5. In combination with a journal box having an opening in the front thereof and having on opposite sides of said opening portions formed in which a lid is received and 95 adapted to be slid to several positions with respect to said opening, of a lid comprising a single flat plate of resilient material bent back upon itself and having a portion at one end bent into a circular form and adapted 100 to engage and latch over the opposite bent over portion.

6. In combination with a journal box having an opening and a recessed portion in the front wall thereof, and also having on opposite sides of said opening portions formed in which a lid is received and adapted to be slid to several positions with respect to said opening, of a single piece of resilient material bent back upon itself and adapted to 105 engage said recessed portion when in an intermediate position and to engage said side portions of said opening in the journal box in its open and closed positions and to be self-sustaining in said positions to form 110 a lid for said journal box.

7. In combination with a journal box having a recessed portion in the front wall thereof, of a lid comprising a single rectangular piece of resilient material bent back 115 upon itself and having an offset portion extending across one side thereof adapted to form an oil shed and also adapted to engage said recessed portion to lock the same in a partly open position.

8. In combination with a journal box hav-

ing a recessed portion in the front wall thereof, of a lid comprising a single piece of resilient material bent back upon itself and having a portion at one end bent into a circular form and adapted to engage and latch over the opposite bent over portion and also having a portion adapted to engage said recessed portion of the box to

hold the same in an intermediate position therein.

Signed at the city, county and State of New York, this 26th day of November, 1913.

HARRY C. GAMAGE.
